FIG. 6.2 is a left side view of the network switch for computers of FIG. 6.1;

FIG. 6.3 is a right side view of the network switch for computers of FIG. 6.1;

FIG. 6.4 is a back view of the network switch for computers of FIG. 6.1;

FIG. 6.5 is a bottom view of the network switch for computers of FIG. 6.1;

FIG. 6.6 is a top view of the network switch for computers of FIG. 6.1;

FIG. 6.7 is a perspective view of the network switch for computers of FIG. 6.1;

FIG. 13.1 is a front view of a second embodiment network switch for computers;

FIG. 13.2 is a back view of the network switch for computers of FIG. 13.1;

FIG. 13.3 is a top view of the network switch for computers of FIG. 13.1;

FIG. 13.4 is a bottom view of the network switch for computers of FIG. 13.1;

FIG. 13.5 is a left side view of the network switch for computers of FIG. 13.1;

FIG. 13.6 is a right side view of the network switch for computers of FIG. 13.1; and

FIG. 13.7 is a perspective view of the network switch for computers of FIG. 13.1.
